GEAR-CUTTING MACHINE

Application filed December 31, 1926. Serial No. 158,844.

The present invention relates to machines for producing gears and particularly to machines in which the blank is given a continuous indexing motion and in which the cutting 5 is effected by a planing tool reciprocated by a crank.

Of the means commonly employed for imparting a reciprocating motion to a planing tool, the crank drive is ordinarily preferred, 10 because of its simplicity. But when a planing tool is reciprocated by means of a crank across the face of a continuously rotating gear blank, a curved slot is cut in the blank which is of double curvature and of general S-shape. 15 As the tool moves along the cut, the clearance angle between the side of the tool and the tooth varies appreciably and this oftentimes causes chatter or produces a poor tooth surface finish. As pointed in our copending application, No. 70,864, filed November 23, 1925, 20 which has matured into Patent No. 1,616,439 of February 8, 1927, these difficulties may be overcome by imparting a further relative movement between the tool and blank at a 25 variable velocity and preferably at a multiple of the frequency of the variable velocity of the tool under actuation of the crank. The present application is a continuation in part of said prior application.

30 One of the objects of the present invention is to provide a modified form of machine operating upon the general principles defined in our application above mentioned.

A further object of this invention is to provide 35 a machine of the type referred to, in which the added variable relative motion is incorporated in the drive to the tool crank.

Other objects of the invention will be apparent hereinafter from the specification and 40 from the recital of the appended claims.

In the accompanying drawings, we have 45 illustrated a preferred embodiment of our invention. It will be understood, however, that the invention is capable of further modifications within its scope and within the limits of the appended claims.

In the drawings:

Figure 1 is a side elevation, partly in section, of a machine constructed according to 50 the preferred embodiment of this invention;

Figure 2 is a sectional plan view of the tool mechanism and cradle;

Figure 3 is a front elevation of the cradle and tool slide; and

Figure 4 is a detail of the tool drive.

The motion imparted to a planing tool by a crank is at a variable velocity and of a simple harmonic nature, the tool moving fastest in the middle of the stroke and slower toward each end. It is this movement of the tool at a variable velocity which combines with the uniform rotary motion of the blank to produce the S-shaped tooth curve. The improvement of our copending application above referred to is based upon the discovery 55 that by imparting another motion at a relative variable velocity between the tool and blank, also of a harmonic nature, but preferably of a different frequency from the harmonic motion of the tool under actuation 60 of the crank, a tooth curve will be produced which will bend throughout its length substantially in one direction. This discovery 65 permits of cutting gears with a substantially uniform tool clearance and gear pairs in 70 which the mating longitudinal tooth curves 75 may be matched exactly or as closely as desired.

The primary purpose of the present invention is to provide a modified form of machine 80 for practising the improved gear cutting process disclosed in our copending application above mentioned. In a machine constructed according to the preferred embodiment of the present invention, the added 85 motion at a variable velocity is incorporated in the tool drive through the rotation of the crank continuously at a variable velocity. In a machine constructed according to this 90 embodiment, a continuous rotary movement at a uniform velocity is imparted to the blank spindle for the purpose of producing a continuous indexing rotation of the blank, the tool is reciprocated by means of a crank or equivalent mechanical element, and the 95 tool crank is driven continuously at a variable velocity. These three movements combine to produce the longitudinal tooth shape.

If it is desired to produce generated gears, an additional generating or rolling motion 100

is imparted between the tool and the blank.

The present invention will be described in connection with a machine for generating bevel gears. It is to be understood, however, that this invention is applicable to the production of other types of gears also, whether generated or non-generated.

In the machine illustrated, the tool is indicated at T. This tool T is mounted upon a tool head 10 which is adjustably secured to the tool slide 11 which is adapted to be reciprocated in guide ways 12 formed in an arm 13 which is pivotally adjustable upon the cradle 14. The cradle 14 is rotatably mounted in bearings 15 and 15' formed in the frame 16 of the machine.

The blank to be cut is secured to a blank spindle 18 which is journaled in a blank support 19. The blank support 19 is adjustable, as will be more particularly described hereinafter, upon the bed or frame 16 so as to permit adjusting the blank to be cut into the proper cutting relation with reference to the tool.

During the operation of the machine illustrated, a reciprocating motion is imparted to the tool, a continuous rotary motion at a uniform velocity is imparted to the blank spindle, and simultaneously a slow rotary movement is imparted to the cradle.

The reciprocating movement of the tool is produced by rotation of the crank 20 which is provided with a spindle 21 which is journaled in a suitable bearing 22 formed in the cradle 14. The crank 20 is operatively connected with the tool slide 11 by means of the connecting rod 23, one end of which is connected with the tool slide 11 by means of the pin 24 and the other end of which is connected with the crank plate by means of the slidably adjustable block 25.

The rotary motion of the crank will impart a motion at a variable velocity of a harmonic nature to the tool. This motion combined with the continuous rotary indexing motion of the blank will produce, as already stated, an S-shaped tooth. We retain the advantages of the crank drive and avoid this form of tooth by driving the tool crank at a variable velocity.

The crank is driven from the motor 28 which is mounted upon a suitable bracket secured to the frame of the machine and which drives through a pair of speed change gears 29 and 30, a stub shaft 31, a bevel pinion 32, and a bevel gear 33, the main drive shaft 34. This main drive shaft 34 is journaled in suitable bearings coaxially of the cradle 14.

Mounted on the drive shaft 34 and connected through a splined connection therewith, is a long-faced helical pinion 35. This pinion 35 meshes with a helical gear 36, which is keyed to the shaft 37, and transmits to the shaft 37, through the gear 36, the rotary motion of the main drive shaft 34.

The helical pinion 35 is provided with a head 38 through which it is rotatably connected with a sleeve 39 which is adapted to be reciprocated at a variable velocity along the drive shaft 34. The sleeve 39 reciprocates in grooves formed in a guide member 40 which is secured to the cradle (Figures 2 and 4).

Any suitable means may be employed for imparting to the sleeve 39 its reciprocating movement, but for this purpose, we, preferably employ a crank 41 which is connected by means of the crank pin 42 with the slidable sleeve 39.

The crank imparts to the sleeve 39 and pinion 35 a reciprocatory motion at a variable velocity of a harmonic nature. Due to the helical nature of the gears 35 and 36, this variable velocity reciprocating motion is combined with the rotational motion of the shaft 34 and transmitted to the shaft 37 as a rotary motion at a variable velocity. The shaft 37 carries a spur pinion 45 which meshes with a spur gear 46 which is secured to the crank plate 20. Through the gearing just described, therefore, the crank is driven continuously at a variable velocity and the tool receives, therefore, a motion which is a combination of two variable velocity motions. When a tool so driven is reciprocated across the face of a continuously rotating blank, if the dimensions of the determining elements are properly chosen, it will cut a groove in the blank which extends substantially in one direction and the tool clearance angle will be substantially constant throughout the length of the cut.

The crank 41 may be driven in any suitable way. As shown, the crank spindle 48 is journaled in a suitable bearing in the cradle 14 and has secured to it intermediate its length a bevel gear 49 which meshes with and is driven by a bevel pinion 50 which is secured to the shaft 37. The gear reduction 50-49 is preferably so proportioned to the reductions 35, 36, 45, 46, that the crank 41 rotates at twice the speed of the tool crank 20 as this has been found to give the best results as regard the tooth curve to be produced.

The machine illustrated is particularly adapted for the cutting of bevel gears. In bevel gear pairs, the pinion is usually much smaller than the gear. To hold the different blanks rigidly during cutting different mountings are ordinarily required for gear and pinion blanks. This usually means that different machines must be employed in cutting gears and pinions. The duplication of machines is avoided with the machine shown by providing means at either end of the blank spindle for securing to one end a gear blank and to the other end a pinion blank and by providing a support for the blank spindle which may be swivelled end for end to bring

either end of the blank spindle and the blank carried thereby into operative relation with the tool. The blank spindle 18, as has already been described, is journaled in a support 19. One end of the blank spindle is constructed so that a gear blank G shown in section in Figure 1 may be secured thereto and the other end of the blank spindle is so formed that a pinion blank P, shown in dotted lines in Figure 1, may be mounted thereon. For this purpose, the blank spindle is provided adjacent one end with a head or shoulder 55 to which is secured the face plate 56. At its opposite end, the blank spindle is provided with an end face of sufficient diameter to form a seat 57 against which the pinion blank P may be firmly clamped.

The face plate 56 serves to support a gear blank, when the machine is to be used in cutting large sized gears, the gear blank G being secured to the face plate by means of the spacing disc 58, the clamps 59, and the bolts 60 which are provided with T-heads which engage in corresponding radial slots 61 formed in the face plate. The disc 58 is brought into clamping engagement with the gear G by means of the tapered clamping member 62 which is adapted to be securely seated in a tapered bore in the blank spindle 18 by means of a threaded rod 63. The rod 63 is provided adjacent its outer end with a head 64 which is adapted to engage the outer end face of the blank spindle. The bolts 60 and the clamps 59 together with the disc 58 and rod 63 serve to securely clamp the gear blank G upon the blank spindle for rotation therewith.

The seat 57 formed by the outer end face of the blank spindle provides a sufficient support for a pinion blank and if a pinion blank P is to be cut, it can be clamped against this seat by means of the rod 63 and clamping plate 64 or by means of a similar rod of suitable length.

The support 19 has formed integral with it, adjacent the pinion end of the blank spindle, a bracket 65 which may serve as a support for a steady-rest for the pinion blank, so that the pinion blank may be held very rigidly during the cutting.

The support 19, as has already been previously stated, is rotatably adjustable on the frame so that either end of the blank spindle may be brought into operative engagement with the tool, so that either a pinion blank or a gear blank may be cut upon the machine, and, the support 19 is formed with an annular bearing 67 which seats on an annular projection 68 formed on a slide 69. The support 19 swivels about an axis coaxial with the bearing 67. The swivelling adjustment of the support 19 is accomplished by rotation of the shaft 70, by means of a wrench, this shaft 70 carrying a spur pinion 71 which meshes with a spur gear 72 which is secured

to the slide 69 and which is mounted coaxially of the bearing 67. Rotation of the shaft 70 moves the support 19 about its axis to bring either end, as may be desired, of the blank spindle into operative relation with reference to the tool. The slide 69, upon which the blank support 19 is swivelled, is in turn mounted upon a bed plate 75 which in turn is mounted on the frame 16 of the machine. The slide 69 is slidably adjustable upon the plate 75 for the purpose of moving the blank to be cut toward and away from the axis of the cradle 13 so as to locate the apex of the blank in the desired relation to the axis of the cradle. In cutting bevel gears, the slide 69 will, preferably, be so adjusted that the axis of the cradle passes through the apex of the blank, so that when the machine is in operation a rolling motion will be imparted between the tool and blank corresponding to the mesh between a gear and crown gear, where the axis of the cradle represents the axis of the crown gear.

The lateral adjustment of the slide 69 is effected by rotation of the shaft 77 and the pinion 78 carried thereby which meshes with a rack 79 which is secured to the plate 75. The slide 69 can be secured in any adjusted position by means of bolts 80 which engage in T-slots 81 formed in the plate 75.

The plate 75 is angularly adjustable about an axis which intersects at right angles the axis of the cradle, so that the blank can be adjusted into the proper cutting plane. For the purpose of this adjustment, the plate 75 is provided with an extension or arm 83 which has a bearing upon a stud 84 secured to the bed 16 of the machine. This adjustment may be effected by rotation of the pinion 85 which meshes with a segment 86 secured to the bed 16.

We shall next describe the means for imparting to the blank its continuous rotary indexing movement. Secured to the main drive shaft 34 (Figure 2) intermediate its length is a bevel gear 90 which meshes with and drives a bevel gear 91 which is fastened to a diagonal shaft 92 (Figures 1 and 2) which is journaled in suitable bearings in the frame or a bracket secured thereto. The shaft 92 carries a bevel gear 93 which meshes with and drives a bevel gear 94 upon a shaft 95. This shaft 95 drives the shaft 96 through the differential gears 97. The shaft 96 drives a telescoping shaft 98 through the bevel gear 99, the bevel gear 100, the sleeve 101 to which this bevel gear is secured, the bevel gear 102, also secured to this sleeve, and the bevel gear 103.

The telescoping shaft 98 carries a bevel gear 104 which meshes with and drives a bevel gear 105 which is secured to an upright shaft 106 that is journaled in the support 19 coaxially of the swivelling axis of this support. The telescoping shaft 98

permits of adjustment of the support 19 about its axis, while the mounting of the bevel gear 105 and shaft 106 coaxially of the swivelling axis of this support 19 permits of continuously driving the shaft 106 regardless of the swivelling adjustment of the support 19, so that motion is transmitted to the shaft 106 in any position of the support 19.

Secured to the shaft 106 is a bevel gear 107 which meshes with a bevel gear 108 upon a stub shaft 109 which is journaled in suitable bearings in the support 19 and which carries a miter gear 110 that meshes with a miter gear 111 upon a transverse shaft journaled in the bracket 19 which drives through the index change gears 112, 113, 114 and 115 the worm shaft 116.

The worm shaft 116 carries a worm 117 which meshes with a worm wheel 118 which is secured to the face plate 56. Through the gearing described, a continuous rotary motion is imparted from the main drive shaft 34 to the blank spindle to rotate the blank continuously on its axis. The worm shaft 116 and the shafts carrying the change gears 112, 113 and 114 are all journaled in the blank support 19 and all moved about the axis of the shaft 106 in the swivelling adjustment of the support 19.

For the purpose of generating the tooth profiles, where generated gears are to be produced, a continuous rotary motion is imparted to the cradle 14. This motion is derived from the shaft 92 (Figures 1 and 2) through the bevel gears 93 and 94 and the shaft 95. The shaft 95 drives a parallel shaft 120 (Figure 2) through the feed change gears 121, 122, 123 and 124, the last being secured to the shaft 120. The shaft 120 carries adjacent its inner end a bevel gear 125 which meshes continuously with two bevel gears 126 and 127 which are loosely journaled upon a transverse shaft 128.

The bevel gears 126 and 127 may be selectively connected to the shaft 128 by means of the yoke 129 which has a splined connection with the shaft 128 and which is movable thereon to engage, through the ratchet teeth with which it is provided at each end, with one or other of the bevel gears 126 and 127. The whole forms a usual type of reversing mechanism, provided in the present machine for the purpose of controlling the direction of rotation of the cradle. The yoke 129 can be moved into engagement with either of the gears 126 or 127 by means of the lever arm 130 (Figure 1) which is pivotally mounted on the frame of the machine.

The transverse shaft 128 carries at its farther end a worm 131 which meshes with and drives a worm wheel 132 secured to the shaft 133 which is journaled in the frame. The shaft 133 carries adjacent one end a worm 134 (Figures 2 and 3) which meshes with a

worm wheel 135 which is keyed to an upright shaft 136 which is suitably journaled in the frame.

The upright shaft 136 carries a worm 137 which meshes with a worm wheel 138 which is secured to the cradle 14. By the means described, a slow rotary motion at a uniform velocity is imparted to the cradle to move the cradle on its axis. The machine illustrated is so constructed that the axis of the cradle intersects the axis of the blank in its apex, when the tool and blank are in proper cutting position. In the machine illustrated, the tool and blank are rolled relatively to each other in a manner corresponding to the rolling motion of a gear and a basic crown gear.

The tool reciprocation and the blank rotation must be so timed relatively to each other that the tool on each succeeding stroke cuts in a new tooth space of the blank. Now the main drive shaft 34 is journaled coaxially of the cradle 14 and it derives its motion directly from the motor and is not affected by movement of the cradle. Because of the slow rotational movement of the cradle, the timed relation between the tool and blank will be disturbed. Some means must be employed, therefore, to compensate for the cradle movement. This might be done by using especially calculated ratios for the change gears, but this would require new calculations whenever the rate of roll is changed and it would also be necessary to carefully reset the tool when starting a new cut. A differential is, therefore, preferably, employed for the purpose as it always maintains the proper relation between the tool, blank and cradle movements independently of the rate and direction of the generating roll.

In the machine illustrated, the differential is incorporated in the blank drive. This differential comprises the differential gears 97 (Figure 1) already mentioned and the housing 140 for these gears.

The compensating motion is effected by rotation of the housing 140. The housing 140 is rotated from the shaft 133 by means of the bevel gears 141 and 142, the transverse shaft 143 (Figure 2), the bevel gears 144 and 145, the shaft 146, the ratio change gears 147, 148, 149, and 150 (Figures 1 and 2), the shaft 151, the spur pinion 152, and the spur gear 153, the latter being secured to the differential housing 140.

By the gearing just described, an additional motion is imparted to the shaft 96, and thence to the blank spindle to compensate for the movement of the cradle thus maintaining the correct timed relation between the tool and blank movements.

With the single differential the ratio change gears 147, 148, 149 and 150 have to be different for cutting gears and pinions of opposite hand of spiral. If it is desired to cut gears of opposite hand on this machine

without recalculating and changing the ratio of the change gears, a second differential may be incorporated in the blank spindle drive according to the principles set out in our co-pending application No. 158,083, filed December 30, 1926.

The adjustments required for positioning the blank in the correct cutting relation with reference to the tool have already been described. The tool adjustments and the mechanism for clapping the tool are substantially the same as those described in our prior Patent No. 1,616,439 already mentioned and they need only be briefly mentioned here as reference can be had to that application for a more detailed description thereof.

The tool T is mounted in a suitable holder which is secured to a clapper block 155 which is pivotally mounted upon a carrier 156. The carrier 156 is provided with an arcuate lower surface which is adjustable upon a corresponding curved seat 157 formed on the tool head 10. The adjustment of the clapper block support 156 on the head 10 permits of positioning the tool so as to cut with the proper clearance angle without in any way affecting the pressure or spiral angles of the gears to be produced.

The head 10 is slidably adjustable upon the tool slide 11, so that the tool can be adjusted toward and from the center of the machine, that is the center of the cradle, for cutting gears of different cone distances. This adjustment can be effected by means such as described in our prior application mentioned. The head 10 can be secured in any adjusted position by means of the bolts 158 which engage in T-slots 159 formed in the slide 11.

The tool slide 11 reciprocates under actuation of the crank 20 and connecting rod 23 in the guide ways 12 formed in the arm 13. This arm 13 is, preferably, pivotally mounted upon the cradle for adjustment about an axis X, Figure 3, which is offset from the axis Y of the cradle. By making this arm adjustable about an offset axis, the tool path can be inclined or offset with reference to the axis of the cradle and the apex of the blank, thereby affording a complete control over the spiral angle to be produced upon the gears to be cut as more particularly described in the copending application referred to. For the purpose of effecting this adjustment the arm 13 carries a gear (not shown) which meshes with the segment 160 (Figures 2 and 3) which is secured to the cradle.

The clapping movement of the tool, effected by movement of the clapper block 155 about its pivot 161, is controlled from the cam 162 which is formed integral with the crank plate 20 (Figure 2) and is accomplished through rotation of this cam, movement of the rod 163 which carries a roller 164 which engages in the cam groove, and movement of the telescoping shaft 165, all operating sub-

stantially as described in our Patent No. 1,616,439 already mentioned.

The tool, as usual, cuts on its stroke in one direction and is out of cutting position on the return stroke. The movement of the blank at a uniform velocity combines with the planing movement of the tool to produce the tooth curve during the cutting operation and acts to index the blank during the period the tool is out of cutting position and is being returned for operation upon a new tooth space.

The machine shown is a single tool machine, but, it will be understood, that by a suitable arrangement two tools may be also employed.

While we have described our invention particularly with reference to a machine for generating bevel gears, it is to be understood that this invention is applicable also to the production of other types of gears, as spur, helical, herringbone, and hypoid, whether generated or non-generated. In the cutting of spur, helical, and herringbone gears, the tool will be reciprocated in a plane parallel to the blank axis according to the principles set forth in our copending application No. 145,903, November 2, 1926. In the cutting of hypoid gears, the blank axis will preferably be offset relative to the axis of the cradle.

In general, it may be said, that while we have described our invention in connection with a specific structure and in connection with specific uses for said structure it is to be understood that the invention is capable of various further modifications and uses and that the structure may be modified within the limits of the invention without departing from its intent or the scope of the following claims and that this application is intended to cover any adaptations, uses, or embodiments, following, in general, the principles of the invention and including such departures from the present disclosure as come within known or customary practice in the gear art and as may be applied to the essential features hereinbefore set forth and as fall within the scope of the invention or the limits of the appended claims.

Having thus described our invention, what we claim is:

1. In a machine for producing gears, a blank support, a blank spindle journaled therein, a tool support, a tool mounted thereon, means for rotating the blank spindle continuously on its axis at a uniform velocity, means adapted to drive the tool at a variable velocity across the face of the blank and means actuating said driving means at a variable velocity, whereby the tool receives a motion which is a combination of two variable movements and which combines with the blank rotation to produce the longitudinal tooth shape.

2. In a machine for producing gears, a

blank support, a blank spindle journaled therein, a tool support, a tool mounted thereon, means for rotating the blank spindle continuously on its axis at a uniform velocity, means adapted to drive the tool across the face of the blank at a variable velocity of a harmonic nature, means for actuating said driving means, including a train of gearing one element of which is driven at a variable 10 velocity of a harmonic nature and at a multiple the speed imparted to the tool driving means by said train, whereby the tool receives a motion which is a combination of two variable movements and which combines with the blank rotation to produce the longitudinal tooth shape.

3. In a machine for producing gears, a blank support, a blank spindle journaled therein, a tool support, a tool mounted thereon, means for rotating the blank spindle continuously on its axis at a uniform velocity, means adapted to drive the tool at a variable velocity across the face of the blank, means for actuating said driving means at a variable 20 velocity, whereby the tool receives a motion which is a combination of two variable movements and which combines with the blank rotation to produce the longitudinal tooth shape, and means for simultaneously producing a relative rolling motion between the tool and blank to generate the tooth profiles.

4. In a machine for producing gears, a blank support, a blank spindle journaled therein, a tool support, a tool mounted thereon, means for rotating the blank spindle continuously on its axis at a uniform velocity, means adapted to drive the tool across the face of the blank at a variable velocity of a harmonic nature, means for actuating said 30 driving means including a train of gearing one element of which is driven at a variable velocity of a harmonic nature and at a multiple the speed imparted to the tool driving means by said train, whereby the tool receives a motion which is a combination of two variable movements and which combines with the blank rotation to produce the longitudinal tooth shape, and means for simultaneously producing a relative rolling motion between the tool and blank to generate the tooth profiles.

5. In a machine for producing gears, a blank support, a blank spindle journaled therein, a tool support, a tool mounted thereon, a cradle upon which one of said supports is mounted, means for rotating the blank spindle continuously on its axis at a uniform velocity, means adapted to drive the tool at a variable velocity across the face of the blank, means for actuating said driving means at a variable velocity, whereby the tool receives a motion which is a combination of two variable movements and which combines with the blank rotation to produce the longitudinal

tooth shape, and means for imparting to the cradle a rotary motion on its axis.

6. In a machine for producing gears, a blank support, a blank spindle journaled therein, a tool support, a tool mounted thereon, a cradle upon which one of said supports is mounted, means for rotating the blank spindle continuously on its axis at a uniform velocity, means adapted to drive the tool across the face of the blank at a variable 70 velocity of a harmonic nature, means for actuating said driving means including a train of gearing, one element of which is driven at a variable velocity of a harmonic nature and at a multiple the speed imparted to the tool driving means by said train, whereby the tool receives a motion which is a combination of two variable movements and which combines with the blank rotation to produce the longitudinal 75 tooth shape, and means for imparting to the cradle, a rotary motion on its axis.

7. In a machine for producing gears, a blank support, a blank spindle journaled therein, a tool support, a tool mounted thereon, means for rotating the blank spindle continuously on its axis at a uniform velocity, a crank for reciprocating the tool across the face of the blank and means for rotating said crank at a variable velocity.

8. In a machine for producing gears, a blank support, a blank spindle journaled therein, a tool support, a tool mounted thereon, means for rotating the blank spindle continuously on its axis at a uniform velocity, a crank for reciprocating the tool across the face of the blank, and means for driving the crank at a variable velocity of a harmonic nature, including a train of gearing, one element of which imparts to the train a variable velocity movement and which is driven at 95 twice the speed of the crank.

9. In a machine for producing gears, a blank support, a blank spindle journaled therein, a tool support, a tool mounted thereon, means for rotating the blank spindle continuously on its axis at a uniform velocity, a crank for reciprocating the tool across the face of the blank, means for rotating the crank at a variable velocity, and means for simultaneously imparting a continuous relative rolling movement between tool and blank 100 to generate the tooth profiles.

10. In a machine for producing gears, a blank support, a blank spindle journaled therein, a tool support, a tool mounted thereon, means for rotating the blank spindle continuously on its axis at a uniform velocity, a crank for reciprocating the tool across the face of the blank and means for driving said crank at a variable velocity of a harmonic nature including a train of gearing, one element of which imparts to the train a variable velocity motion and which is driven at a 115 multiple the speed of the crank, and means for simultaneously producing a continuous 120 125 130

relative rolling movement between the tool and blank to generate the tooth profiles.

11. In a machine for producing gears, a blank support, a blank spindle journaled therein, a tool support, a tool mounted thereon, a cradle upon which one of said supports is mounted, means for rotating the blank spindle continuously on its axis at a uniform velocity, a crank for reciprocating the tool across the face of the blank, means for rotating said crank at a variable velocity, and means for simultaneously imparting a continuous rotary movement to the cradle on its axis.

12. In a machine for producing gears, a blank support, a blank spindle journaled therein, a tool support, a tool mounted thereon, a cradle upon which one of said supports is mounted, means for rotating the blank spindle continuously on its axis at a uniform velocity, a crank for reciprocating the tool across the face of the blank, means for driving said crank at a variable velocity including a train of gearing, one element of which imparts to the train a variable velocity movement of a harmonic nature, and which is driven at twice the speed of the crank, and means for simultaneously imparting to the cradle a continuous movement on its axis.

13. In a machine for producing gears, a blank support, a blank spindle journaled therein, a tool support, a tool mounted thereon, means for rotating the blank spindle continuously on its axis at a uniform velocity, a crank for reciprocating the tool across the face of the blank, means for driving the crank continuously at a variable velocity, including a train of gearing one element of which is driven by a second crank and means for driving the second crank at a multiple the speed of the tool crank.

14. In a machine for producing gears, a blank support, a blank spindle journaled therein, a tool support, a tool mounted thereon, means for rotating the blank spindle continuously on its axis at a uniform velocity, a crank for reciprocating the tool across the face of the blank, means for driving the crank continuously at a variable velocity including a train of gearing, one element of which is driven by a second crank, and means for rotating the second crank twice for each complete revolution of the tool crank.

15. In a machine for producing gears, a blank support, a blank spindle journaled thereon, a tool support, a tool mounted thereon, means for rotating the blank spindle continuously on its axis at a uniform velocity, a crank for reciprocating the tool across the face of the blank, means for driving the crank continuously at a variable velocity including a train of gearing, one element of which is driven by a second crank, means for driving the second crank at a multiple of the speed of the tool crank, and means for simultane-

ously producing a relative rolling motion between the tool and blank to generate the tooth profiles.

16. In a machine for producing gears, a blank support, a blank spindle journaled therein, a tool support, a tool mounted thereon, a cradle upon which one of said supports is mounted, means for rotating the blank spindle continuously on its axis at a uniform velocity, a crank for reciprocating the tool across the face of the blank, means for driving the crank continuously at a variable velocity including a train of gearing one element of which is driven by a second crank, and means for driving said second crank at a multiple the speed of the tool crank rotation, and means for simultaneously imparting to said cradle a continuous rotary movement on its axis.

17. In a machine for producing gears, a blank support, a blank spindle journaled therein, a tool support, a tool mounted thereon, means for rotating the blank spindle continuously on its axis at a uniform velocity, a crank for reciprocating the tool across the face of the blank, means for driving the crank including a pair of helical gears, means for imparting a continuous rotary motion to said gears, and means for simultaneously reciprocating one of said gears axially at a variable velocity a plurality of times for each complete revolution of the tool crank.

18. In a machine for producing gears, a blank support, a blank spindle journaled therein, a tool support, a tool mounted thereon, means for rotating the blank continuously on its axis at a uniform velocity, a crank for reciprocating the tool, means for driving the crank including a pair of helical gears, means for imparting a continuous rotary motion to said gears, and means for simultaneously reciprocating one of said gears axially at a variable velocity a plurality of times during each complete revolution of the crank, and means for simultaneously producing a relative rolling motion between the tool and blank to generate the tooth profiles.

19. In a machine for producing gears, a blank support, a blank spindle journaled therein, a tool support, a tool mounted thereon, a cradle upon which one of said supports is mounted, means for rotating the blank spindle continuously on its axis at a uniform velocity, a crank for reciprocating the tool across the face of the blank, means for driving the crank including a pair of helical gears, means for imparting a continuous rotary motion to said gears and means for simultaneously reciprocating one of said gears axially at a variable velocity a plurality of times for each complete revolution of the tool crank, and means for simultaneously imparting to the cradle a continuous rotary movement on its axis.

20. In a machine for producing gears, a

blank support, a blank spindle journaled therein, a tool support, a tool mounted thereon, means for moving the tool at a variable velocity across the face of the blank, means for rotating the blank spindle continuously on its axis at a uniform velocity, and means for simultaneously imparting between tool and blank an additional movement at a variable velocity, said means including a pair of helical gears, means for rotating the gears continuously and means for simultaneously reciprocating one of said gears axially at a variable velocity.

21. In a machine for producing gears, a blank support, a blank spindle journaled thereon, a tool support, a tool mounted thereon, a carrier upon which one of said supports is mounted, means for moving the tool at a variable velocity across the face of the blank, means for rotating the blank spindle continuously on its axis at a uniform velocity, means for imparting a continuous movement to said carrier, and means for simultaneously imparting between tool and blank an additional movement at a variable velocity, said means including a pair of helical gears, means for rotating said gears continuously, and means for simultaneously reciprocating one of said gears axially at a variable velocity.

22. In a machine for producing gears, a blank support, a blank spindle journaled therein, a tool support, a tool mounted thereon, a crank for reciprocating the tool at a variable velocity across the face of the blank, means for rotating the blank spindle continuously on its axis at a uniform velocity, and means for simultaneously imparting between the tool and blank an additional movement at a variable velocity, said means including a pair of helical gears, means for continuously rotating said gears, and means for reciprocating one of said gears axially at a variable velocity a plurality of times during each revolution of the crank.

23. In a machine for producing gears, a blank support, a blank spindle journaled therein, a tool support, a tool mounted thereon, a carrier upon which one of said supports is mounted, a crank for reciprocating the tool across the face of the blank, means for rotating the blank spindle continuously on its axis at a uniform velocity, means for simultaneously imparting to said carrier a continuous movement, and means for simultaneously imparting between the tool and blank an additional movement at a variable velocity, said means including a pair of helical gears, means for rotating the gears continuously, and means for reciprocating one of said gears axially at a variable velocity a plurality of times during each revolution of the tool crank.

24. In a machine for producing gears, a blank support, a blank spindle journaled

therein, a tool support, a tool mounted thereon, a crank for reciprocating the tool, means for rotating the blank spindle continuously on its axis at a uniform velocity, a cradle upon which one of said supports is mounted, means for imparting to said cradle a continuous rotary movement on its axis and means for simultaneously imparting between tool and blank an additional movement at a variable velocity, said means including a pair of helical gears, means for rotating the gears continuously, and means for reciprocating one of said gears axially at a variable velocity a plurality of times during each rotation of the tool crank.

25. In a machine for producing gears, a blank support, a blank spindle journaled thereon, a tool support, a tool mounted thereon, means for rotating the blank spindle continuously on its axis at a uniform velocity, a crank for reciprocating the tool across the face of the blank, means for driving the crank including a pair of helical gears, means for imparting a continuous rotary motion at a uniform velocity to said gears, and means for simultaneously reciprocating one of said gears axially at a variable velocity.

26. The combination with a driven shaft, a driving shaft and means for driving the first shaft from the second, including a pair of helical gears, one of which is fixedly secured to said driven shaft and the other of which is slidably mounted on the drive shaft but is held against rotation relative thereto, of means for rotating the driving shaft and means for simultaneously reciprocating said second gear, thereby to impart to said driven shaft a movement which is the resultant of the reciprocating and rotary motions of said second helical gear.

27. The combination with a driven shaft, a driving shaft, and means for driving the first shaft from the second including a pair of helical gears, one of which is fixedly secured to the driven shaft, and the other of which is slidably mounted on the driving shaft but is held against rotation relative thereto, of means for rotating the driving shaft continuously at a uniform velocity and means for simultaneously reciprocating said second gear at a variable velocity, whereby to impart to said driven shaft a movement at a variable velocity which is a resultant of the reciprocating and rotary motions of said second helical gear.
